CORPORATION, OF MERIDEN, CONNECTICUT, A CORPORATION OF DELAWARE

ELECTRIC SNAP SWITCH

Application filed November 27, 1928. Serial No. 322,135.

Our invention relates particularly to switches having a ratchet action of the rotary type and it is especially designed for use in circuits where it is required to carry 5 110 volts.

The main object is to provide a simple inexpensive but reliable mechanism which can be readily mounted in the panel board of a radio set or the like.

10 In carrying out the invention we provide a housing having a sleeve adapted to be supported in the panel board. The stationary contacts are supported in an insulating disc in the rear of the housing and the rotary switch 15 member and ratchet mechanism are mounted on a shaft or spindle which is supported at the rear end in the disc and at the front in the sleeve of the housing.

Fig. 1 is a side view of a device embodying 20 our invention showing it supported in a panel board.

Fig. 2 is a rear view of the device.

Fig. 3 is a longitudinal sectional view of the device on a larger scale.

25 Fig. 4 is a front view of the insulating disc which supports the stationary contacts.

Fig. 5 is a perspective view showing one of the stationary contacts and its terminal strip.

30 Fig. 6 is a detail view of the conducting part of the rotary switch member.

Fig. 7 is a side view and partial section of an insulating collar forming part of the rotary switch member.

35 Fig. 8 is a detail view of the metal part of the ratchet member.

Fig. 9 is a detail view of an insulating washer forming part of the ratchet member.

40 Fig. 10 is a side view of the main shaft or spindle.

The sleeve 11 which serves as the main support is adapted to be mounted in a panel board or other support 12 to which it may be secured by clamp nuts 13.

45 The shaft 14 may be of metal and extends through the sleeve 11 in which it is rotatable. The shell 15 of the housing is secured to the sleeve of the housing in any suitable manner.

50 The disc 16 may be formed of insulating

material to fit the rear end of the shell 15. The end 17 of the shaft is reduced in diameter and extends through the disc 16 and is riveted over the washer 18. A fibre washer 19 may be employed to cover the rear face 55 of the disc 16 and the end of the shaft. The disc is provided with laterally projecting lugs 20 which fit in corresponding slots 21 in the sides of the shell 15 to prevent relative rotation. The rear edge of the shell is provided with lugs 22 which are bent over at the rear to hold the washer 19 and disc 16 60 in place in the housing.

The disc 16 is provided with four inclined segments 23 and 24 arranged in pairs. The stationary contacts 25 are inclined similarly and provided with terminal strips 26 which extend through passages 27 in the disc 16. Lugs 28 are partially cut from the sides of 65 these strips and bent over as shown in Figs. 2 and 3 to hold the terminal strips and their contacts in place.

The rotary switch member has a ring 29 with inclined spring arms 30 adapted to be rotated over the surface of the inclines 24 and the contacts 25 in one direction. This member 29 is also provided with ratchet teeth 31 inclined in the opposite direction to the direction of inclination of the arms 30. The insulating collar 32 fits in the opening in the 70 ring 29 and has a flange 33 which extends over the ring 29.

The ratchet member consists of a metal ring 34 and an insulating washer 35. The ring has inclined ratchet teeth 36 adapted to 75 coact with the teeth 31. It also has ears 37 adapted to be bent over into the notches 39 in the edges of the washer 35. The washer has a central opening 38 adapted to receive the shaft 14. The spring 40 on the shaft 14 80 presses at one end against the U-shaped washer 41 and at the other against the ratchet member 35. The U-shaped or forked washer 41 is slipped into a groove 42 in the shaft and 85 may serve as a bearing for the shaft in the recess 43 in the sleeve. The switch is operated by rotating the shaft 14 by any suitable means.

When the shaft is rotated in a right hand direction the rotary switch member is ro- 90 95 100

tated through the instrumentality of the washer 35 and ratchet member 34, the teeth 36 engaging the backs of the teeth 31. The switch may thus be rotated step by step as the 5 arms snap from the inclines 24 on to the inclined contacts 25 and off again, thus affording a double make and break with a snap action. In case the switch knob or lever is rotated backward, that is, in a left hand, 10 direction, the ratchet teeth 36 will ride up the inclined teeth 31 without effecting the switch or injuring any of the parts.

We claim:

1. A snap switch comprising a supporting 15 sleeve, a housing carried thereby, an insulating disc closing the rear end of said housing contacts carried by said disc, an operating shaft rotatably supported at the rear in said disc and near the front supported in said 20 sleeve, a rotatable switch member mounted on said shaft but insulated therefrom and a spring pressed ratchet member insulated from said shaft and co-acting with said switch member.

2. A snap switch comprising a supporting 25 sleeve, a housing carried thereby, a molded insulating disc closing the rear end of said housing contacts carried by said disc, an operating shaft rotatably supported in said 30 disc, a fibre disc covering the rear end of said shaft, a rotatable switch member mounted on said shaft but insulated therefrom and a spring pressed ratchet member insulated from said shaft and co-acting with said 35 switch member.

3. A snap switch comprising a supporting sleeve, a housing carried thereby, an insulating disc closing the rear end of said housing, said housing and disc having interfitting 40 parts to prevent relative rotation, contacts carried by said disc, an operating shaft rotatably supported at the rear in said disc, a rotatable switch member mounted on said shaft but insulated therefrom and a ratchet 45 member insulated from said shaft and co-acting with said switch member.

4. A snap switch comprising an insulating disc having ratchet teeth at the front, contact segments on two oppositely disposed teeth having conducting strips integral therewith extending rearwardly through said disc for circuit connections in the rear, a shaft rotatably supported by the disc and a ratchet operated switch member carried by said 55 shaft and coacting with said contact segments and ratchet teeth.

5. A snap switch comprising an insulating disc having ratchet teeth in the front, contact segments on two oppositely disposed teeth having conducting strips integral therewith extending rearwardly through said disc for circuit connections in the rear, said strips having ears bent over at the rear of said disc, a shaft rotatably supported by the disc and a switch member carried by said shaft and co-

acting with said contact segments and ratchet teeth.

6. A snap switch comprising an insulating disc having inclined segments at the front, contact segments on two oppositely disposed inclined segments having conducting strips integral therewith extending through said disc for circuit connections, a shaft rotatably supported by the disc, at the rear a ratchet operated switch member carried by said shaft and coacting with said contact segments and ratchet teeth, a spring and an abutment washer on said shaft, and a housing for said parts including a supporting sleeve, said washer being located in said sleeve.

7. A snap switch comprising a disc having a number of pairs of inclined ratchet teeth at least two of said teeth being formed of conducting material to constitute stationary contacts, a shaft rotatably supported in said disc and insulated from said contacts, a rotatable switch member mounted on said shaft and consisting of an insulating collar and a metal spider having oppositely disposed inclined contact arms coacting with the stationary contacts and having projecting ratchet teeth, a ratchet member rotatable with said shaft and consisting of a fibre washer and a metal ring secured thereto and having outwardly projecting inclined lugs coacting with the ratchet teeth on said rotary switch member and a spring mounted on said shaft and pressing said ratchet member towards said switch member.
